US00D779355S

(12) **United States Design Patent** (10) Patent No.: **US D779,355 S**
 (45) Date of Patent: **** Feb. 21, 2017**

(54) **ROPE FORMED BY INTERLOCKING STITCHES FOR USE IN JEWELRY, CLOTHING, ACCESSORIES, OR APPLIED TO THE SURFACE OF ARTICLES OF MANUFACTURE**

(71) Applicant: **Leonard Bridges**, Highland Park, NJ (US)

(72) Inventor: **Leonard Bridges**, Highland Park, NJ (US)

(**) Term: **15 Years**

(21) Appl. No.: **29/549,170**

(22) Filed: **Dec. 18, 2015**

Related U.S. Application Data

(62) Division of application No. 29/501,664, filed on Sep. 6, 2014, now Pat. No. Des. 747,996.

CLAIM

The ornamental design for a rope formed by interlocking stitches for use in jewelry, clothing, accessories, or applied to the surface of articles of manufacture, as shown.

DESCRIPTION

FIG. 1 is a perspective view of a rope formed by interlocking stitches for use in jewelry, clothing, accessories, or applied to the surface of articles of manufacture, showing my new design.

FIG. 2 is a front view thereof; and,

FIG. 3 is a side view thereof.
